UNITED STATES PATENT OFFICE.

CHARLES E. EATON, OF CHELSEA, MASSACHUSETTS.

FAN ATTACHMENT.

SPECIFICATION forming part of Letters Patent No. 322,530, dated July 21, 1885.

Application filed May 26, 1884. (Model.)

To all whom it may concern:

Be it known that I, CHARLES E. EATON, of Chelsea, in the county of Suffolk and State of Massachusetts, have invented a new and useful Improvement in Fans for Rocking Chairs, which will, in connection with the accompanying drawings, be hereinafter fully described, and specifically defined in the appended claims.

10 This invention has for its object the production of an improved fan adapted to be readily attached to and removed from rocking chairs, and when so attached to be automatically actuated by the rocking of the chair; 15 and it consists in the construction and combination of the divers devices embodied therein, as hereinafter more particularly and fully set forth and claimed.

Figure 1 is a side elevation of a chair with 20 my invention thereto applied. Fig. 2 is an elevation taken as from the left hand in Fig. 1, and showing the lower portion of my invention with the means of attaching it to the chair-rocker, which latter is shown in transverse section. Fig. 3 is a detached elevation 25 taken from the same standpoint as Fig. 2, and showing the upper part of my invention. Fig. 4 is a top or plan view of the standard. Fig. 5 is an inverted or under side view of the fan- 30 supporting bracket.

In said views A represents a chair, which is introduced for the purpose of illustrating my invention. B is a rocker of the chair; C, a side bar of the seat-base, and D an arm 35 piece or rest. An angle-iron, E, having a horizontal arm, a, curved to correspond to rocker B, and a vertical arm, b, is removably secured to the rocker by means of projecting angles d d, formed on arm a, and the thumb- 40 screws e therein, threaded, as shown in Figs. 1 2. The upper reduced end, j, of vertical arm b is inclined outward, as shown in Fig. 2, to make room for the upholstery upon arm-piece D; and in the upper edge or face of said part 45 j, I form in the same horizontal plane a series of angular indentations, k, as shown in Fig. 1, for interlocking therewith the fan-supporting standard m, which has formed upon its inner face, one above the other, a series of hooks, q, 50 formed to embrace the upper end of arm b, as shown in Fig. 2 at j, and with a salient angle between the hook q and body of the standard

m, to enter and engage the corresponding indentations in the head of arm b, as shown in Fig. 1.

In the lower end of standard m is formed the open slot p, which receives the stud l, formed on arm b, as shown in Figs. 1, 2, said slot being of such length as to allow either of hooks q to be interlocked in the head of arm b, as stated, and as the size of the person occupying the chair may require, the fan carried by the standard to be at greater or less distance above the seat C, while, by means of the series of indentations k, the standard may 65 be arranged toward the front or back of the chair to suit the wishes of the occupant, the stud l being the pivot of motion of the standard m when so adjusted in indentations k.

The fan F is preferably formed with four 70 wings, u, secured to spindle t by the socketed brackets a', or in any suitable manner. The fan-spindle t is journaled in arms s, extending from shank i of the spindle-carrying bracket, said shank i being journaled in bosses n of 75 standard m, as shown in Fig. 3.

Upon the rear end of arm a, I pivot a lever, f, near its lineal center, and in the end of this lever is pivoted the truck h, while to the forward end of said lever I secure cord x, which 80 passes thence upward alongside standard m and within the groove in the face of guiding-pulley z, pivoted on an ear of the standard, whence it passes over the grooved pulley b', secured on fan-spindle t, and thence descends 85 to and is secured to the upper end of spiral spring y, the lower end of which is attached to stud l of arm b, which stud extends through slot p of standard m, as stated, the spring serving to secure the standard on said stud.

It will be obvious that when the chair is rocked backward the forward end of lever f will be depressed by the action of stud g and truck h, and that by the action of cord x spring y will be elongated, and that the tension upon 95 the cord, caused by the resistance of said spring, will cause it to rotate the fan; and when the chair is rocked forward the counter-action of the spring will impart a reverse movement to the fan; and hence as the chair 100 is rocked backward and forward a reciprocating rotary movement of the fan will be maintained.

For convenience in seating one's self in or

rising from the chair a fin, *v*, is formed on the fan-bracket at the junction of its spindle *i* and arms *s*, and a corresponding recess, *w*, is formed in the head of standard *m*, both at its 5 outer side and front edge, said fin being seated in the former-stated recess when operative; but by slightly raising the fan, which spring *y* readily admits, it may be turned toward the back of the chair, when said fin will be seated 10 in the recess at the front of the standard, and so held until changed to the position shown in Fig. 1 for use.

Instead of angle-iron *E*, the arm *b* for supporting standard *m* and the pivot of lever *f* 15 may be independent each of the other; but the angle-iron is preferable, as thereby the apparatus may be removed from the chair and replaced without care in adjusting the parts, each having, by reason of said angle-iron, its 20 proper position relatively to the other. A thin stay, *c*, is shown as uniting and strengthening the arms of said angle-iron.

I am aware that it is not new to produce the reciprocating rotation of a fan attached to 25 a chair by means of a lever and spring united by a cord, the lever being actuated by the rocking motion of the chair, and the spring being actuated by the lever through the cord. Hence I do not broadly claim such device; 30 but

What I do claim as my invention is—

1. The fan-supporting standard formed with indentations *w w*, and the fan-bracket formed with a pivoted stem or shank, *i*, and 35 fin *v*, to interlock in said indentations, whereby the fan may be arranged and secured to extend over the occupant of the chair or parallel with the side of the chair, substantially as specified.

40 2. The fan-supporting standard *m*, formed with a series of hooks, *q*, arranged one above the other, in combination with a support

adapted to be secured to the chair and to be engaged by said hooks, substantially as specified.

45

3. The combination, with angle-iron *E*, formed with arm *a*, having clamps *d* formed thereon, and also formed with vertical arm *b*, having indentations *k* arranged along the line of its upper end, of a fan-support formed and 50 adapted to be engaged with said angle-iron, substantially as specified.

4. The combination, with the fan-supporting standard *m*, having a series of hooks, *q*, arranged one above the other, of angle-iron 55 *E*, having arm *b*, formed with a series of indentations, *k*, arranged along the line of its upper end and respectively adapted to receive said hooks, substantially as specified.

5. The combination, with standard *m*, 60 formed with hooks *q*, arranged one above the other, and with a longitudinal slot, *p*, near its lower end, of angle-iron *E*, formed with arm *b*, having stud *l*, adapted to engage in said slot, and a series of indentations, *k*, arranged 65 along the line of its upper end and adapted to be engaged by said hooks, substantially as specified.

6. The combination of standard *m*, having a series of hooks, *q*, arranged one above the 70 other, angle-iron *E*, formed with arm *a*, having clamps *d*, and stud *g*, and arm *b*, having stud *l*, and a series of notches, *k*, arranged 75 along the line of its top, lever *f*, having truck *h* and pivoted on stud *g*, spiral-spring *y*, and cord *x*, secured at one end to the free arm of lever *f* and at the other to said spring, and engaging pulley *b'* on the fan-spindle, substantially as specified.

CHARLES E. EATON.
